ACCESS COVER FOR AN ELECTRIC CIRCUIT BREAKER HOUSING

Ernest M. Bevilacqua, Springdale, and Andrew T. Kostanecki and Eliot Noyes, New Canaan, Conn., assignors to General Electric Company, a corporation of New York

Filed Nov. 2, 1961, Ser. No. 67,353

Term of patent 14 years

(Cl. D26—13)

FIG. 1.

FIG. 2.

FIG. 3.

FIG. 1 is a front elevational view of an access cover for an electric circuit breaker housing, showing our new design;

FIG. 2 is a side elevational view of the cover shown in FIG. 1, the opposite side having a similar appearance; and

FIG. 3 is a perspective view of the cover shown in FIGS. 1 and 2.

We claim:

The ornamental design for an access cover for an electric circuit breaker housing, as shown and described.
